UNITED STATES PATENT OFFICE.

BERNHARD J. SYNSTELIEN, OF FONDA, IOWA.

CORN-CARRYING ATTACHMENT FOR CORN PICKING AND HUSKING MACHINES.

Application filed September 3, 1925. Serial No. 54,244.

To all whom it may concern:

Be it known that I, BERNHARD J. SYNSTELIEN, a citizen of the United States, residing at Fonda, in the county of Pocahontas and State of Iowa, have invented certain new and useful Improvements in Corn-Carrying Attachments for Corn Picking and Husking Machines; and I do hereby declare the following to be a full, clear, and exact description of the invention, such as will enable others skilled in the art to which it appertains to make and use the same.

My invention has for its object to provide a corn-carrying attachment for corn-picking and husking machines and is in the nature of an improvement on my U. S. Letters Patent of the same title, issued October 14, 1924, under Number 1,511,244.

To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary plan view of the main frame and running gear of a corn-picking and husking machine, and also illustrating in section a portion of the supplemental frame of the attachment;

Fig. 2 is a perspective view of the attachment and a portion of the main frame with the carrier in a dumping position;

Fig. 3 is an elevation of the gate end of the carrier;

Fig. 4 is a view of the attachment partly in side elevation and partly in vertical section; and

Fig. 5 is a side elevation of the carrier showing a modified form of guide flange.

The numeral 6 indicates the main frame of a corn-picking and husking machine supported on an axle 7 on which is journaled a pair of wheels 8 having hub caps 9. A tongue 10 is rigidly secured to the main frame 6 and may be attached to a tractor or other motive power for drawing the corn-picking and husking machine.

The attachment includes a supplemental frame comprising pairs of inner and outer angle uprights 11 and 12, respectively, rigidly secured to the main frame 6 at the right side thereof. The outer uprights 12 are

rigidly connected at their upper ends by a top bar 13, and which uprights are held in vertical positions by means of a pair of inclined brace rods 14, the lower ends of which are anchored to the left side of the main frame 6, and their upper ends are adjustably anchored to the top bar 13.

A pair of track rails 15 that extend transversely of said machine have their outer ends pivoted at 16 to the intermediate portions of the uprights 12, and their inner ends are secured to the inner uprights 11 by nut-equipped bolts 17 adapted to be inserted through any horizontally aligned pair of holes 18 in said uprights. Brace rods 19 have one of their ends pivoted to the uprights 12, below the track rails 15, and their other ends are secured to the track rails 15 by nut-equipped bolts 20 adapted to be inserted through any horizontally aligned pair of holes 21 in said track rails. The track rails 15 are in the form of angle bars, the horizontal flanges of which are turned toward each other and the vertical flanges of which are turned upward. A cross-tie angle bar 22 rigidly connects the outer end of the track rails 15, and an inner cross-tie angle bar 23 rigidly connects the inner ends thereof and affords a stop for a purpose which will presently appear.

A traveling tiltable box-like dumping carrier 24 is mounted on the supplemental frame and has secured to its under side a pair of rack bars 25 which extend parallel to the track rails 15. These rack bars 25 are supported on and mesh with pinions 26 secured to a shaft 27 journaled in bearings on the outer ends of the track rails 15. A pair of rollers 28 are journaled in bearings secured to the under side of the carrier 24 at the inner end thereof and are arranged to run on the horizontal flanges of the track rails 15. The vertical flanges of the track rails 15 afford stops for the rack bars 25 and rollers 28 and thereby prevent lateral movement of the dumping carrier 24 and hold the same for straight line traveling movement transversely of the main frame 6.

A pair of cam-acting guide flanges 29 are secured to the sides of the dumping carrier 24 and work between vertically spaced roller guide studs 30 on the uprights 12.

The guide studs are made vertically adjustable by having their journals removably mounted in different vertically spaced holes

in the uprights 21. The front end of the carrier 24 is closed by a swinging gate 31 the upper edge of which is hinged at 32 to a transverse bar 33 secured to the sides of said carrier and extending thereabove. A spring-projected latch 34 on the swinging gate 31 is arranged to engage a lock detent 35 secured to the carrier 24. A cable 36 is attached to the latch bolt 34 and to the top cross-tie bar 13 for releasing said latch bolt when the carrier 24 is moved into a dumping position. A tumbling rod 37 is connected to the front end of the shaft 27 by a universal joint 38.

15 As shown, the track rails 15 are secured in an inclined position and normally the rollers 28 rest on said track rail and engage the rear cross-tie bar 23 as a stop and hold the carrier 24 in a tilted loading position, and which position is such that the corn discharged from the elevator of the corn-picking and husking machine will fall into said carrier. Journalled on the shaft 27 adjacent to the pinions 26 are rollers 26', on which flanges of the bars 25 are arranged to ride and tilt, as best shown in Fig. 3. By operating the tumbling rod 37 from a driven part of the machine or in any other suitable manner, the pinions 26 acting on the 20 rack bars 25 will move the carrier 24 upward and outward on the track rails 15 and on the rollers 26' until the same becomes overbalanced, and at which time, said carrier will rock on the rollers 26', lift the rollers 28 from the track rails 15 and tilt into a dumping position which, as shown, is reversely inclined from its loading position. During the 25 tilting movement of the carrier 24 into a dumping position, the movements thereof are controlled by the guide flanges 29 and co-operating studs 30. At the completion of the dumping movement of the carrier 24, the slack in the cable 36 will be taken up to release the latch bolt 34 and thereby permit the door 31 to swing open as the load in the carrier 24 is discharged. After the load is dumped from the carrier 24, said carrier is returned to loading position by reversely operating the tumbling rod 37. The initial 30 return movement of the carrier 24 will bring the rear curved end portions of the guide flanges 29 into contact with the upper studs 30 which will cam the inner end of the carrier 24 downward and thereby reversely tilt the same so that its rollers 28 will again re-engage the track rails 15 and travel therealong until stopped by the rear cross-tie bar 23. During the return movement of the carrier to loading position, the gate 31 will swing closed and thereby cause the lock bolt 34 to automatically interlock with the detent 35. When the track rails 15 are set, as shown in Figs. 3 and 4, the final movement of the carrier 24 into a dumping or loading position will be under the action of gravity.

By vertically adjusting the track rails 15 on the inner uprights 11, the inclination of said track rails may be varied, at will, either above or below a horizontal position of said track rails. In case the track rails 15 are 70 adjusted so that they incline above a horizontal position, the carrier 24 will move in an inclined position without having a tilting action. In this arrangement of the track rails 15 suitable latching mechanism would 75 have to be provided for holding the carrier 24 in a loading position.

Referring now to the modification shown in Fig. 5, the guide flanges 39 are adjustably secured to the carrier 40 for vertical and 80 horizontal movements by means of bolts secured in said flanges and adapted to be inserted through any horizontally aligned pairs of vertically and horizontally spaced holes in the sides of said carrier.

By raising and lowering the guide flanges 39 on the carrier 40 and raising the respective studs on the uprights 12, the inclination of said carrier when in dumping position, may be varied, at will; or by adjusting said 90 flanges inward or outward the carrier will be caused to dump sooner or later.

What I claim is:

1. The combination with a frame, of a traveling carrier mounted for movement to and from reversely inclined positions, a pair of oblique rails on which said carrier travels when in one of its inclined positions, guides on the carrier, abutments on the frame with which said guides move to support the carrier when in its other inclined position and guide the same from one inclined position to the other, and propelling means for the carrier.

2. The combination with a frame, of a driven shaft journaled on the frame and having a pair of toothed wheels, a carrier having racks meshing with the wheels and supporting said carrier for movements to and from reversely inclined positions, a pair of oblique track rails, a pair of rollers on the carrier adapted to run on said rails during the movement of the carrier in one of its inclined positions, a pair of guide flanges on the carrier, and a pair of rollers on the frame on which the guide flanges move during the movement of the carrier in its other inclined position and for guiding the carrier from one of its inclined positions to the other.

3. The structure defined in claim 2 in which the carrier is gravity-tilted from the track rails and tilted by the guide flanges onto said rails.

4. An attachment of the kind described comprising a supplemental frame having a pair of track rails, driven toothed wheels journaled on said rails, a traveling tiltable dumping carrier having racks meshing with said wheels and supporting said carrier,

wheels journaled on said carrier and arranged to travel on said rails, guide flanges on said carrier, and studs on said frame cooperating with the guide flanges.

5. The structure defined in claim 4 in which the guide flanges and studs are vertically adjustable on said frame.

6. The structure defined in claim 4 in

which the guide flanges are vertically adjustable on said carrier.

7. The structure defined in claim 4 in which the guide flanges are endwise adjustable on said carrier.

In testimony whereof I affix my signature.

BERNHARD J. SYNSTELIEN.
